DISPLAY CASE

John H. Reese, Madison, Wis., assignor to The Electric Storage Battery Company, Philadelphia, Pa., a corporation of New Jersey

Filed Apr. 24, 1962, Ser. No. 69,824

Term of patent 14 years

(Cl. D80—11)

FIG. 1

FIG. 2

FIG. 3

FIG. 4

FIG. 5

FIG. 1 is a perspective view taken from the front left side of a display case showing my new design;

FIG. 2 is a left side elevational view thereof, the right side being substantially the same as the side shown;

FIG. 3 is a rear elevational view of the rear thereof;

FIG. 4 is an enlarged vertical sectional view thereof taken on line 4—4 of FIG. 1; and FIG. 5 is an enlarged fragmentary cross-sectional view thereof taken on lines 5—5 of FIG. 2.

The essential feature of my design resides in the arrangement of the specific shelving and battery compartments in association with the cabinet as shown.

I claim:

The ornamental design for a display case, as shown and described.
